Fig. 6

Fig. 7

Fig. 8

FIG. 1 is a perspective view of a plaque embodying my new design;

FIG. 2 is a side elevational view;

FIG. 3 is a top plan view; and

FIG. 4 is a bottom plan view thereof.

FIG. 5 is a perspective view of another embodiment of my new design wherein the raised rectangular areas on the lower half of the front have been omitted and the top and bottom have been modified;

FIG. 6 is a side elevational view;

FIG. 7 is a top plan view; and

FIG. 8 is a sectional view taken on the line 8—8 of FIG. 5.

I claim:

The ornamental design for a plaque, as shown and described.
